CLARENCE E. BEACH AND LEE J. VOORHEES, OF BINGHAMTON, NEW YORK, ASSIGNEES,
BY MESNE ASSIGNMENTS, TO THE GAMEWELL FIRE ALARM TELEGRAPH COMPANY,
A CORPORATION OF NEW YORK.

NON-INTERFERENCE SIGNAL-BOX.

1,207,838.

Specification of Letters Patent. Patented Dec. 12, 1916.

Application filed February 23, 1915. Serial No. 9,990.

To all whom it may concern:

Be it known that we, CLARENCE E. BEACH and LEE J. VOORHEES, citizens of the United States, residing at Binghamton, in the county of Broome and State of New York, have invented certain new and useful Improvements in Non-Interference Signal-Boxes, of which the following is a specification.

This invention is particularly adapted for use in noninterference signal boxes which are arranged both to control the effectiveness of the signaling contacts and to control the running of the signaling train; although certain features of this invention are adapted for use either separately or in combination with each other with many types of noninterference boxes, and certain features of this invention may be employed without other features to produce a highly efficient noninterference box, while with the addition of other features a noninterference and succession box is provided, and certain other features are adapted for a separate use in connection with various forms of succession boxes.

An object of this invention is to provide a noninterference box in which the force of the noninterference magnet is more effectively applied, so as to require the expenditure of less electrical energy in attaining positive action in noninterference mechanism.

Another object of this invention is to provide an absolute noninterference mechanism, adapted for use with various types of signal boxes, which will not act to interrupt the transmission of a signal because of weakness of line current unless such current is substantially decreased after the transmission of a signal has been initiated.

Other objects of this invention are to produce an absolute noninterference signal box devoid of fine adjustments, economical to manufacture, and not requiring skilled maintenance or readjustment in service.

Still other objects are referred to in the following specification and more particularly pointed out in the claims.

In attaining the feature of this invention whereby the force of the noninterference magnet of a signal box is more effectively

applied, an operating force is provided for disabling mechanism adapted to prevent or defeat the operation of the signaling contacts by the train, the structure moved by said force being adapted to move independently of the noninterference armature, and carrying a part moving through a comparatively large range and adapted to be latched when the armature is in one position and unlatched by a comparatively small movement of the armature toward its other position, so that the energy which must be applied to the armature by the noninterference magnet need only be such as will overcome the friction due to such engagement, and the armature is not required at any time to move against the pull of such force, or to store up energy therein. Said operating force is applied to such part at varying advantage so that, when restrained by the armature controlled latch, said force will be acting at minimum advantage and therefore the frictional load to be overcome by the movement of the armature is decreased to a minimum.

In attaining the feature of this invention whereby an absolute noninterference signal box will not act to interrupt the transmission of a signal because of such weakness of line current that the noninterference magnet will not be adequately energized during closures incident to the transmission of a signal to prevent the noninterference mechanism acting to disable or defeat the action of the circuit controllers, a part moved by the train is so connected with the noninterference armature that such part will act just prior to the commencement of the test period preceding the transmission of any signal, to apply a retractile force to said armature substantially greater than any retractile force applied thereto during the transmission of any signal.

In the drawings accompanying and forming part of this application, a signal box is shown embodying all of the features of this invention in a preferred form, but this invention is not limited to the structure shown, as many parts may be added or omitted, and the form and arrangement of parts may be altered in many respects, without departing from the spirit of this invention.

In the accompanying drawings, in which

like reference characters denote the same parts throughout, Figure 1 is a front elevation of a noninterfering and succession signaling box embodying the features of this invention; Fig. 2 is a top view of the signal box shown in Fig. 1, with the noninterference magnet removed; Fig. 3 is an enlarged perspective view of the signaling contacts shown in Fig. 1 together with the magnetically controlled disabling means therefor; Fig. 4 is an enlarged perspective view of the structure of the signal box shown in Fig. 1 whereby the noninterference armature is enabled to control the disabling means for the circuit controllers, and the armature controlled stopping mechanism for the signaling train; Fig. 5 is an elevation of the manually disengageable stopping mechanism of the signal box shown in Fig. 1, and parts coöperating therewith and Fig. 6 is another detail view illustrating particularly the restoring lever.

Referring to Figs. 1 and 3, the armature 11 is mounted on the carrier 13 in suitable relation to the noninterference magnet 12. The carrier 13 is pivoted on the shaft 14 and one end of the retractile spring 15 is connected to said carrier. A determining lever 16 is loosely pivoted upon the shaft 14 and has an end 17 disposed in the path of the armature 11. A spring 18 forms a yielding connection between the determining lever 16 and the carrier 13 and tends constantly to hold the end 17 of the determining lever 16 in engagement with the armature 11. The projections 19 and 20 carried by the determining lever 16 are adapted to form controlling means for parts engaging therewith, as hereinafter more fully pointed out. An extension 22 from the carrier 13 is provided with a stud 23 and the depending hook wire 24. (See Figs. 2 and 5.) A suitable signaling train is provided comprising the shaft 25, gear 26 and clockwork arranged to drive and govern the speed of said shaft and gear in any well known manner. The escape wheel 27 is suitably driven by the gear 26, and said escape wheel engages with the pallet 28, said escape wheel 50 and pallet, with the fan 29 mounted on the pallet shaft, acting to govern the speed of rotation of the gear 26. A manually disengageable stopping mechanism is provided for the gear 26 comprising the stop arm 30, the lug 31 carried by said arm being adapted to engage with the pin 32 carried by the gear 26 when said arm is in a certain position; and to be moved out of the path of said pin when said arm is in another position. A suitable manual operating lever 33 is provided for manually raising the stop arm 30, and a prop 34 having a shoulder 35 and inclined face 36 adjacent thereto is so mounted in the path of the pin or projection 37 carried by the stop arm 30 that

when the stop arm is moved to a position which carries the lug 31 out of the path of the pin 32, the pin 37 will be engaged by the shoulder 35 due to the action of the spring 38 which tends to swing the shoulder 35 under said pin 37. When the prop 34 is moved far enough against the tendency of the spring 38 to withdraw the shoulder 35 from the path of the pin 37, the pin may ride along the inclined face 36 and thereby move the prop 34 a further distance against the tendency of the spring 38. A spring 39 is so applied to the stop arm 30 as to tend to draw said arm toward the stop 40 where the lug 31 will be brought into the path of the pin 32. Separately insulated contacts 41 and 42 are mounted in suitable relation to the arm 30, and a shunting contact 43 is mounted upon the insulating material 44 which is secured to the free end of the stop arm 30 in such position that when said stop arm rests against the stop 40 said shunting contact 43 will connect the contacts 41 and 42, and when the pin 37 is supported by the shoulder 35, said contact 43 will be ineffective. A stop 45 is mounted in the path of the stop arm 30 in such position as to arrest the movement of said arm when it has been raised high enough to allow the shoulder 35 to pass under the pin 37. The worm 46 is fixed upon the shaft 25, one end of said worm being provided with a flange 47 and the other end of said worm being provided with a pin or abutment 48.

The thread 49 is so formed in said worm that a tracer engaging said worm will be moved away from the flange 47 and toward the abutment 48 when the shaft 25 revolves in normal direction. The tracer 50 is connected to the prop 34 by means of the universal joint 51, the free end of said tracer being adapted to be brought into engagement with the thread 49. The pin 52 is carried by the prop 34 in such position with relation to the tracer 50 that when said prop has been moved, through the engagement of the pin 37 with the inclined face 36, the free end of said tracer will be raised out of the path of the pin 48 and out of the thread 49. The spring 53 is so connected between the tracer 50 and the pin 52 as to tend to bring the free end of the tracer into engagement with the thread 49 and away from the end of the worm adjacent to the abutment 48. The above parts hence constitute means for withdrawing the tracer from the worm and out of the path of said abutment when the prop is moved to a predetermined position.

The tracer 50 is mounted in such relation to the hook wire 24 that when the armature 11 is in its retracted position, said hook wire will hold the tracer out of engagement with the worm 46. The relative construction and arrangement of the free end of the tracer 50 and the flange 47 is such that said flange 130

will arrest the movement of said tracer in response to its spring 53 before the engaging end of said tracer is moved far enough away from the abutment 48 to be carried beyond the end of the thread 49 farthest therefrom. The abutment 48 is so positioned with relation to the flange 47 that when the tracer 50 is brought into engagement with the thread 49 at the end thereof nearest to said flange, said tracer will be brought into the path of the abutment 48 when the shaft 25 has made such number of revolutions as will cause the desired operation of the signaling contacts, and the engagement of the abutment 48 with the tracer 50 will swing the prop 34 far enough to withdraw the shoulder 35 from the path of the pin 37 so that the arm 30 will be pulled down by the spring 39, thus carrying the pin 37 along the inclined face 36 and swinging the prop 34 far enough to cause the tracer 50 to be disengaged from the abutment 48 through the action of the pin 52, whereupon the spring 53 will swing said tracer 50 against the flange 47, and such dropping of the arm 30 will carry the lug 31 in the path of the pin 32 and thus arrest the running of the train.

Signal formulating mechanism is provided comprising contact operating means moved by the signaling train, signaling levers adapted to be operated thereby, and circuit controlling or signaling contacts carried by said levers.

The contact operating means consists of a signal wheel having suitable teeth and notches formed therein for imparting the intended movement to the signaling contacts, and for economy in manufacture, and convenient adaptability should comprise the sections 54 and 55 which are fixed upon the shaft 25 (see Fig. 3). The front section 54 of the signal wheel has notches corresponding with the closures of the signal to be transmitted, while the rear section 55 has notches corresponding with the breaks of the signal to be transmitted.

The signaling lever 56 is loosely pivoted at 57 and is provided with a projection 58 adapted to drop into the notches in the front section 54 of the signal wheel, and the signaling lever 59 is also pivoted at 57 and has a projection 60 adapted to drop into the notches in the rear section 55 of the signal wheel. The circuit closing contact 61 is mounted upon, but suitably insulated from, the signaling lever 56 near the free end thereof and comprises a jaw contact. The circuit opening blade contact 62 is similarly mounted near the free end of the signaling lever 59. The various parts of this signal formulating mechanism are of such relative construction and arrangement that as the shaft 25 is turned in its normal direction 65 such relative movement of the contacts 61

and 62 will be obtained as will alternately bring said contacts into engagement with each other and separate them.

The sections 54 and 55 are maintained in suitable position with relation to one another by means of the pin 63 passing therethrough, and said sections are so arranged that their relative positions upon the shaft 25 may be reversed, so that the section 55 will be so placed as to coengage with the projection 58 and section 54 will engage with projection 60. When these sections are arranged as shown in Fig. 3 the operation of said sections will cause such relative movement of the signaling contacts 61 and 62 as will produce makes and breaks of the circuit such as are characteristic of a so-called "open type" signal wheel and when these sections are reversed, so that the section 55 is in front and the section 54 is mounted behind it, the signal transmitted will be that characteristic of a so-called "closed type" signal wheel. In any event the section engaging with the projection 58 will raise the lever 56 to a point so high that the contact 61 carried thereby will be above the limit of the travel which may be imparted to the contact 62 by the section of the signal wheel engaging with the projection 60, and the notches are always so arranged in the two sections that when the lever 59 has been raised through the engagement of the inclined face of any notch with the projection 60, and before said lever is raised to the highest point to which it is carried by the section coengaging therewith, the projection 58 will be permitted to drop into a notch in the front section so as to provide an instantaneous action in closing the circuit, and thereafter when an inclined face of any notch of the front section is in close proximity to the inclined face of the projection 58 but just before engaging therewith a notch in the rear section will be presented to the projection 60 and thus allow the arm 59 to drop just before the arm 56 is so raised as to carry the contact 61 away from the contact 62, and thus provide instantaneous action in opening the circuit.

Inasmuch as the contact 61 always acts to instantaneously close the circuit, and the contact 62 always acts to instantaneously open the circuit, said contacts are herein referred to as circuit closing and circuit opening contacts respectively.

A stop 64 is carried by the circuit opening contact 62 and is arranged to limit the distance which said contact blade 62 may enter the contact jaws 61, so that said contact jaws 62 may be formed of pliable material so as to permit the blade 62 to readily penetrate between them and thereby obtain a rubbing contact on both sides of said blade similar to that of an ordinary knife switch while

preventing such a degree of engagement as would cause the projection 58 to be prematurely brought into engagement with the inclined face of any notch of the front section 54.

While it is preferable to use the contacts 61 and 62 carried by the signaling levers 56 and 59, respectively, so as to obtain the instantaneous action both in making and breaking the circuit, it is evident that many features of this invention may be advantageously utilized in connection with other well known forms of circuit controlling contacts, but in any event the contacts must be so controlled by the signaling lever 59 that the circuit will be closed when said lever is raised by the signal wheel, and the circuit will be opened when said lever is allowed to fall.

20 The end of the signaling lever 59 is extended in the direction of the projection 20, and is so formed in relation thereto that when the projection 60 has dropped into any of the notches of the section of the signal wheel coöperating therewith, said end will lie in the path of the projection 20 and thereby hold the determining lever 16 in position to retain the armature 11 in attracted position and when said signaling lever 59 occupies a position at or above that to which it may be raised by the engagement of the signal wheel therewith, the said end of said signaling lever will be raised above the projection 20 and thus permit the retraction 35 of the armature 11.

The catch arm 65 is pivoted on the signaling lever 59 at 66 and carries a projection 67 which, for convenience in manufacture, extends in the path of the rear section 53 of the signal wheel so that said catch arm may be raised and dropped substantially in step with the vibrations of said signaling lever 59, in any event this catch arm must be raised just prior to the initiation of the 45 transmission of a signal, and should not be raised at any time when the signal wheel is not in position to support the signaling lever 59 through its engagement with the projection 60 thereof, for reasons which will 50 be hereinafter more fully explained.

A catch 68 is carried by the catch arm 65 and is arranged to project rearwardly from said arm past the signaling lever 59. A holder 69 is pivoted at 70 and has the shoulder 71 adapted to be engaged by the catch 68 and has the holding notch 72 and the hook 73 formed therein. A projection 74 is carried by the signaling lever 59 in such relation with the holder 69 that when 60 said holder is in position to permit the shoulder 71 to be engaged by the catch 68, the hook 73 will engage the projection 74 and hold the signaling lever 59 in such position that the circuit opening contact 62 will be held in engagement with the circuit closing

contact 61, and will raise said contact 61 high enough to carry the projection 58 out of the path of the section 54 of the signal wheel, and so that when said holder is in another position, the holding notch 72 will 70 lie in the path of said projection 74 and thus prevent the signaling lever 59 from rising high enough to maintain a connection between the contacts 61 and 62 when the signaling lever 59 has been raised to the limit 75 of the travel which may be imparted thereto by the signal wheel.

The hook 73 is so formed and bears such relation with the pivot 70 that when the holder 69 is moved from the position where the notch 72 is in the path of the projection 74 to the position where the shoulder 71 may be engaged by the catch 68, the engagement of said hook 73 with the projection 74 will raise the arm 59 to the position already described. The holder 69 and the parts co-operating with said holder therefore constitute disabling mechanism for moving the circuit controlling contact 62 to a position above that to which it may be moved by the engagement of the rear section of the signal wheel with the projection 60 of the signaling lever 59.

The operating spring 75 is so applied to the signaling lever 59 as to tend to hold the projection 58 in engagement with the signal wheel. The operating spring 76 is so applied to the catch arm 65 as to tend to maintain both the signaling lever 59 and the projection 67 carried by the catch arm 65 in engagement with the signal wheel. In other words, the operating spring is so applied to the catch arm that either the projection 67 or the catch 68 may act as a fulcrum around which said arm may be rocked by said spring and through its pivot connection 66 holds the signaling lever 59 in engagement with the signal wheel. The catch arm 65 therefore forms means operable by the train whereby the movement of the disabling mechanism, comprising the holder 69, from its disabling position where it holds the signaling lever 59 in elevated position to the position where it will permit the projection 60 carried by said signaling 100 lever to drop into the notches in the rear section of the signal wheel and thus produce breaks in the signaling circuit, will be permitted only when said rear section is 105 in position to support said projection 60 in elevated position, which position occurs only during closures of the signaling contacts. The arm 77 is fixed upon the shaft 78 which shaft also has the stop arm 30 fixed thereon in suitable relation to the arm 77 so that said arms 30 and 77 will move together.

The restoring lever 79 see Fig. 6 is pivoted on the frame at 80 and one end of said restoring lever is adapted to be engaged by the free end of the arm 77 so as to be moved 130

- thereby and the other end of said restoring lever carries the pivot 81, which has the extension 82 thereupon which lies in the path of the signaling lever 59, and is so positioned in relation thereto that when the restoring lever 79 occupies the position in which it will be held by the arm 77 when the stop arm 30 is in such position that the lug 31 thereon lies in the path of pin 32, said extension 82 will 10 raise the signaling lever 59 to the position to which it may be raised by the engagement therewith of the hook 73 carried by the holder 69. Said pivot 81 and extension 82 therefore constitute a connection operated by 15 the restoring lever 79 adapted to act to render the contacts 61 and 62 unresponsive to the running of the train whenever the stop arm 30 is in position to arrest the running of the train.
- 20 The latch arm 83 is mounted upon the pivot 81 to turn freely thereon, and the hook 84 is formed in the free end of said latch arm in suitable relation to the projection 19 so that when the determining lever 16 is in 25 one position; said projection 19 will lie in the path of said hook and so that said projection will be withdrawn from the path of said hook when said lever 16 is moved by a very slight retractive movement of the armature 11. The slanting face 85 is formed in suitable relation to the hook 84 so that when said hook is below the projection 19 and the latch arm 83 is raised while the armature 11 is in attracted position, said 30 slanting face will engage with the projection 19 and thereby swing the lever 16 to carry said projection out of the path of said hook and permit the latch arm 83 to be raised to a position where said projection 19 may be 40 carried in the path of hook 84 and thereby latch said hook.

The projection 86 carried by the latch arm 83 is so formed with relation to the tongue 87 formed in the signal wheel hub 88 that the engagement of said tongue with said projection may impart such movement to the latch arm 83 as will raise the hook 84 to latching position where it may be engaged by the projection 19. Said projection 86 45 and tongue 87 therefore form means operated by the train in running for adjusting the retractile spring 15 of the latch arm 83 to apply a maximum tension to the noninterference armature 11 at least once during 50 each rotation of the signal wheel.

The cam face 89 is carried by the latch arm 83 in such position with relation to the holder 69 that when the restoring lever 79 is in the position which it occupies when the stop arm 30 is in position to arrest the running of the train, the engagement of said cam face with the face 90 of the holder 69 will be such as to swing said holder to the 60 position where it will permit the signaling lever 59 to be raised out of engagement with

the signal wheel, and where it will carry the shoulder 71 in position to be engaged by the catch 68, and so that when the restoring lever 79 is in the position which it occupies when the stop arm 30 has been raised until the 70 pin 37 is supported by the shoulder 35, said cam face will permit the holder 69 to move to the position which will carry the hook 73 out of the path of the projection 74 and will bring the holding notch 72 in the path of 75 said projection 74 when the latch arm 83 is in position where it holds the hook 84 in position to be engaged by the projection 19, and so that when the latch arm has turned on its pivot 81 so that the hook 84 is a 80 suitable distance below the projection 19, said cam face will move the holder 69 to the position where the hook 73 will engage the projection 74.

From the foregoing it will be seen that the 85 latch arm 83 and the holder 69 and parts co-operating therewith form disabling means controlled by the noninterference armature constantly tending to act to render the signaling contacts unresponsive to the running 90 of the train.

It will further be seen that the cam face 89 forms a slack connection between the latch arm 83 and the holder 69 whereby the downward movement of the latch arm after 95 it has been disengaged from the projection 19 may move the holder to disable the signaling contacts and may retain the holder in disabling position without thereby obstructing the movement of the latch arm 100 as the hook 84 is out of the path of the projection 19 when said latch arm is in disabling position.

An end of the armature retractile spring 105 15 is so connected to the latch arm 83 as to constantly impart thereto a tendency to move counterclockwise, and so that when the hook 84 is in engagement with the projection 19, the operative effect of said spring upon said latch arm will be applied thereto 110 only at such advantage as to be capable of safely moving said latch arm against the friction of its pivot in counterclockwise direction, and so that the operative effect of 115 said spring will be applied to said latch arm when the hook 84 has moved out of engagement with the projection 19 in counterclockwise direction at such advantage as to be capable of safely moving said latch arm to operate the holder 69 to raise the signaling 120 levers 59 and 56, and such amount of travel is permitted the latch arm 83 that, when said latch arm has so moved, the tension of said spring will be materially decreased and therefore the retractile force applied by said spring to the armature 11 when the latch arm 83 has acted to disable the signaling contacts will be substantially less than when said contacts are free to act. The latch arm 83 therefore forms an operating means 125 130

for the disabling mechanism, and is controlled by the armature through the engagement of the hook 84 with the projection 19, and the spring 15 constantly imposes a tendency to said latch arm to act to move the holder 69, forming part of the disabling mechanism, to the position where it will render the contacts 61 and 62 unresponsive to the running of the train.

10 The hub 88 should preferably be mounted upon the shaft 25 in such position with relation to the pin 32 that when said pin is holding the train at rest by engagement with the lug 31, the tongue 87 will support the latch arm 83 in such position that it may be raised to the position where the hook 84 may be engaged by the projection 19 when the train is set in motion, and so that when the train is set in motion, said tongue will be 15 quickly withdrawn from the path of the projection 86 so as to permit the latch arm 83 to drop if not supported by the projection 19 remaining in the path of said hook 84.

10 The detent 91 has the forked end 92 adapted to receive the stud 23 so as to be moved thereby, and said detent is pivoted at 93 to the restoring lever 79 near the end of said lever which carries the pivot 81. The end 94 of the detent 91 is so formed that it is 25 adapted to engage the fan 29 to stop the train, and said detent is so constructed and arranged that when the restoring lever 79 is in the position which it occupies when the lug 31 is in the path of the pin 32 said detent 30 will be rendered ineffective to engage the fan 29, through the lifting of the pivot 93 carrying the end 94 out of the path of said fan, but when the lever 79 is in the position which it occupies when the pin 37 is supported by the shoulder 35, the pivot 93 35 will be dropped far enough so that when the stud 23 is in the position which it occupies when the armature 11 is in retracted position, the end 94 will lie in the path of the fan 29 and thus arrest the running of the train, and when the armature 11 is in attracted position the stud 23 will swing the detent 91 so as to carry the end 94 out of the path of said fan.

40 When this signal box is in normal condition (as shown in Figs. 1, 2 and 5),—the stop arm 30 is held by the spring 39 in engagement with the stop 40, thereby holding the lug 31 in the path of the pin 32; the restoring lever 79 is held by the arm 30 acting through the arm 77, in such position that,—the pivot 93 of the detent 91 maintains the free end 94 of said detent out of the path of the fan 29, the extension 82 45 maintains the signaling lever 59 in elevated position, and the engagement of the cam face 89 with the face 90 maintains the holder 69 in locking position, thereby permitting the catch 68 to lie in the path of the shoulder 71 of said holder. The tongue

57 is in such engagement with the projection 86 that it maintains the latch arm 83 in such partially elevated position that, when the pivot 81 is moved downwardly, said latch arm 83 will rock upon the projection 86 and thereby raise its hooked end 84 to a point which will bring said hook in the path of and slightly below the upper edge of the projection 19, and will bring the projection 86 in such relation to the tongue 87 that a 62 comparatively slight movement of the shaft 25 will carry said tongue 87 out of the path of said projection 86. The prop 34 is maintained in its extreme left hand position by the engagement of the pin 37 with the inclined face 36 thereof, and thereby holds the tracer 50 out of the path of the abutment 48 and thread 49 of the worm 46 by means of the pin 52 carried by said prop 34. Owing to the stop arm 30 being in its lower 67 position, the noninterference magnet and the signaling contacts will be shunted by the shunt connection established between the contacts 41 and 42 by the contact 43 held in engagement therewith, and the armature 11 72 is in retracted position, holding the projection 19 out of the path of the hook 84 and the projection 20 in the path of the free end of lever 59.

77 The operation of this signal box to condition it for the transmission of a signal is, for convenience, herein referred to as "pulling" the box, and is accomplished by pressing downwardly upon the handle mounted upon the front end of the operating lever 100 83 (see Figs. 1 and 2). Such pulling of this box acts to condition it for operation as follows:—The movement of lever 33 lifts stop arm 30, thereby so moving the contact 43 as to break the shunt around the signaling contacts and the noninterference magnet, and carrying the pin 37 out of the path of the inclined face 36 and above the shoulder 35. Whereupon the prop 34 will move to such position as to bring said shoulder 105 35 into the path of said pin 37, to retain the stop arm in elevated position, and to withdraw the pin 52 from supporting the tracer 50, so as to leave the tracer 50 free 110 to be moved by the spring 53 into engagement with the thread 49 of the worm 46 whenever the armature 11 moves to attracted position, and the final upward movement of the stop arm 30 carries the lug 31 out of the path of the pin 32 and thereby disengages the stopping mechanism from the train. The coincident movement of the restoring lever 79 so lowers the pivot 93 as to bring the end 94 of the detent 91 into the 115 path of the fan 29 if the armature 11 is in retracted position, and such movement of the restoring lever 79 also lowers the pivot 81 so as to carry the cam face 89 out of the path of the curved face 90 of the holder 69, and carries the extension 82 out of the path 120

of movement of the signaling lever 59. Said holder will be held against such movement as will release the signaling lever 59 by the engagement of its shoulder 71 with the 5 catch 68.

The operation of this box after being pulled in a normal circuit at a time when no other signal is in course of transmission upon said circuit is as follows: When the 10 contact 43 is withdrawn from engagement with the contacts 41 and 42 all the line current will be forced to flow through the non-interference magnet 12, and said magnet will thereupon be energized and cause the 15 armature 11 to move against the tension of the springs 15 and 18, the tension of the spring 18 being applied because the determining lever 16 is held against movement with the armature 11 by the presence of the 20 hook 84 in the path of the projection 19, and such movement of the armature 11 will further act to withdraw the end 94 of the detent 91 from the path of the fan 29 and thereby permit the train to run, and will 25 permit the tracer 50 to move into engagement with the thread 49 of the worm 46. When the train commences to run in response to its being released from the restraint of the detent 91, the action of the 30 tongue 87 upon the projection 85 will raise the arm 83 somewhat higher, thereby imparting additional tension to the armature retractile spring 15 while continuing to apply the tension of the spring 18, both of 35 said springs thus tending to retract the armature 11, however, the armature 11 will remain in attracted position because the normal line current which is flowing through the magnet 12 sufficiently energizes magnet 40 12 to overcome both of said springs, and the continued movement of the tongue 87 will raise the latch arm 83 high enough to carry the hook 84 above the projection 19, whereupon the spring 18 will swing the lever 16 so as to carry the projection 19 into 45 the path of the hook 84, and at the same time swing the projection 20 out of the path of the free end of the signaling lever 59, and thereafter a slight additional movement of 50 the shaft 25 will carry the tongue 87 out of the path of the projection 86, and thus permit the hook 84 to drop upon and be supported by the projection 19. The signal wheel sections being arranged as shown in 55 Fig. 3, so that the makes and breaks of the signaling circuit will be those characteristic of the operation of a so-called "open type" signal wheel, the train will continue running for a time longer than the longest closure in any signal, and throughout said time a notch in the section 55 of the signal wheel will be presented to the projections 60 and 67, but at the termination of such time such notch will end, and the inclined face to the 60 right of such notch will be brought into

engagement with the projection 67 and thereby raise the catch arm 65 so as to withdraw the catch 68 from the path of the shoulder 71, whereupon the operating spring 76 will rock the catch arm 65 upon the projection 67 so as to move the signaling lever 59 downwardly and thereby swing the holder 69 to the right far enough to bring the shoulder 71 to the right of and below the left hand face of the catch 68 and bring the projection 60 into engagement with the raised portion to the right of said inclined face, and said raised portion of the signal wheel will prevent the signaling lever 59 from dropping far enough to open the circuit between the signaling contacts. When said inclined face of the section 55 of the signal wheel is thus brought in the path of the projection 60, a notch in the section 54 will be presented to the projection 58. After the shaft 25 has further rotated a suitable distance, the inclined face to the right of such notch in the section 54 will be brought adjacent to the said projection 58, and thereupon a notch in the section 55 will be brought into the path of the projection 60, whereupon the signaling lever 59 will drop, and the downward movement of the signaling lever 56 will be so arrested as to permit the circuit opening contact 62 to be moved out of engagement with the circuit closing contact 61 through the action of the operating spring 76. If however said contacts are welded or for any other reason stick together, the engagement of the inclined face of the notch in the section 54 of the signal wheel will raise the signaling lever 56 still higher, and thus bring the projection 74 carried by the signaling lever 59 into engagement with the holding notch 72 in the holder 69, thereby arresting the upward movement of the signaling lever 59, and applying the force of the running train to assist the spring 76 in separating said contacts. Thus in any event the contacts will become separated, and the movement of contact 62 away from the contact 61 will be practically instantaneous, and thereby effectively break the circuit between said contacts, and as the signaling lever 59 drops in carrying the contact 62 away from the contact 61, the free end of said lever will pass to the right of the projection 20 and thus lock the determining lever 16 and the armature 11 against retractive movement. Upon further rotation of the shaft 25 the inclined wall to the right of the notch in section 55 into which projection 60 has 120 dropped will raise the signaling lever 59 almost to the position where the contact 62 125 will touch the contact 61 before a notch in section 54 is presented to the projection 58 of the signaling lever 56, and thereupon such notch will be presented and allow the said signaling lever 56 to drop and thus instant- 130

taneously close the current path between said contacts, and thereafter the further rotation of the shaft 25 will cause the signaling lever 59 to be raised slightly higher so as to bring the free end of said lever above the projection 20 and thereby permit retractive movement of the armature 11 during the time that said signaling lever 59 is in elevated position. The continued rotation of the shaft 25 will bring the various notches and raised portions of the sections 54 and 55 of the signal wheel into engagement with the projections 58, 60 and 67 and thereby cause such relative movement of the signaling contacts as will produce the intended makes and breaks in the circuit connected thereto. As the shaft 25 revolves the tracer 50 will be carried against the tension of spring 53 toward the path of the abutment 48 by its engagement with the thread 49 and, upon said shaft 25 completing the intended number of rotations, the abutment 48 will be brought into engagement with the free end of said tracer 50, and will act through said tracer to force the prop 34 to such position as will withdraw the shoulder 35 from the path of the pin 37, whereupon the spring 39 will move the stop arm 30 downwardly and thus carry the pin 37 in engagement with the inclined face 36 so as to swing the prop 34 to a position where the pin 52 carried by said prop will lift the tracer 50 out of the thread 49 and out of the path of the abutment 48, so that said tracer will swing toward the flange 47 in response to the tendency of the spring 53. Upon this downward movement of the stop arm 30 the shunt contact 43 will connect with contacts 41 and 42, the lug 31 will be brought into the path of the pin 32, the end 94 of the detent 91 will be carried out of the path of the fan 29, the extension 82 will raise the signaling lever 59 to its upper position, the cam face 89 will swing the holder 69 so as to permit the signaling lever 59 to be so raised and to permit the catch 68 to move into the path of the shoulder 71 of said holder, and the armature 11 will be permitted to move to retracted position owing to the free end of the signaling lever 59 being thus raised and the magnet 12 being deenergized due to the closing of the shunt contacts 41, 42 and 43, but the train will continue running until the pin 32 is brought into engagement with the lug 31, thus returning all parts to their normal condition.

The operation of this box if pulled when the line circuit is broken does not extend beyond the operation of parts described in connection with the pulling of the box as, since the armature 11 remains in retracted position, the end 94 of the detent 91 is brought into the path of the fan 29 when the stop arm 30 is manually raised before the lug 31 is wholly withdrawn from the path of the

pin 32, and no movement of the train will therefore take place so long as the circuit stands open.

The operation of this box when it has been pulled on open circuit and the circuit is subsequently closed, is as follows: When this box is pulled on open circuit, the train is held against running by the engagement of the end 94 of detent 91 with the fan 29 as just described, but when the circuit is closed while the box is so held against running, the energization of the magnet 12 incident to said closure will cause the armature 11 to move to attracted position and thus swing the detent 91 to such position that the end 94 will be withdrawn from the path of the fan 29, and if the signaling circuit remains closed thereafter at points external to this box, the operation of the box will continue as hereinbefore described in connection with the pulling of the box under normal circuit conditions.

The operation of this box when pulled after another box has commenced the transmission of its signal, is as follows: If, at the instant that this box is pulled, the line circuit stands open incident to the transmission of the signal of the box already in control of the line, the end 94 of the detent 91 will remain in engagement with the fan 29, and the train of this box will not commence to operate until the circuit is again closed. However upon the first closure of the circuit, after this box is pulled, incident to the transmission of such other signal, the end 94 of the detent 91 will be withdrawn from the fan 29 and the train of this box will commence to run, and upon each break following such a closure, the armature 11 will retract and the end 94 will again engage the fan 29 and stop the train. After one or more of such closures, the shaft 25 will have been permitted to rotate far enough to withdraw the tongue 87 from the path of projection 86, whereupon the latch arm 83 will move downwardly in response to the tension of the retractile spring 15. As the train runs for a time longer than the longest closure in any signal after the disengagement of the tongue 87 from the projection 86 and before the signaling contacts are permitted to act to make the first break for the signal, it is evident that any closure which causes the detent 91 to be withdrawn from the path of the fan 29 at a time when such withdrawal will permit the tongue 87 to be carried out of the path of the projection 86 will end before such test period has been completed, and thereupon the armature 11 will retract, carrying the projection 19 out of the path of the hook 74, whereupon the arm 83 will move downwardly and thus swing the cam face 89 to a position which will cause the hook 73 to engage the projection 74 and lock the signaling lever 59 in elevated position.

tion. While the latch arm 83 is in its lower position, the rotation of the signal wheel will not result in the engagement thereof with the projections 58 and 60 of the signaling levers and therefore no relative movement of the signaling contacts will result from such rotation of the signal wheel, but, during all breaks in the signaling circuit the detent 91 will engage the fan 29 and prevent the signaling train from running, and during closed circuit intervals the armature 11 will move to attracted position and thus withdraw the detent 91 from the path of the fan 29 and permit the signaling train to run. With the signal wheel sections arranged, as already stated, to cause the formulation of a signal characteristic of a so-called "open type" signal wheel, the closures are of very short duration and merely last long enough before each break to give ample time for the magnets in the circuit to properly respond to the current flow therethrough, and during all of the remaining interval between breaks the circuit is held open, therefore it will be found that the shaft 25 will make less than one revolution as the result of the closures resulting from the transmission of the desired number of rounds comprising the signal of another box, and, when the signal of such other box has been completed and the circuit is finally closed thereafter, the armature 11 of this box will move to and remain in attracted position and this box will run until the tongue 87 engages the projection 86 and thus raises the latch arm 83 and carries the hook 84 past the projection 19, in doing which the face 85 of said hook will force the projection 19 slightly to the right until said hook 84 is above said projection, whereupon the spring 18 will swing said projection into the path of said hook and immediately thereafter the tongue 87 will disengage the projection 86 and this box will then proceed with the transmission of its signal in the manner already described.

If two of these boxes are pulled at or about the same time, so that the signal wheels of such boxes reach the point where they are adapted to act to cause the circuit to be broken, at the signaling contacts one slightly ahead of the other, it is evident that upon the circuit being broken by the contacts of the box which first acts to break the circuit, the armature of the other of said boxes will retract and its latch arm 83 will drop and thereby lock its signaling contacts. After the first box has completed the transmission of its signal, the second box will proceed in the manner hereinbefore described, as when pulled after another box has commenced the transmission of its signal. The operation of two of these boxes if pulled so as to break the circuit at their respective signaling contacts simul-

taneously is as follows: The determining levers 16 of both boxes will be locked upon the first break in the circuit as both signaling levers 59 will drop at the same time, and thereafter the signaling levers of said boxes may operate in unison for several strokes if the trains of such boxes are so nicely adjusted that the notches in their respective signal wheels will be presented to their corresponding co-engaging signaling levers at exactly the same time, but upon the first occasion when the signaling lever 59 of one of said boxes drops, or is in its lower position, at a time when the signaling lever 59 of the other of said boxes is raised high enough to bring its free end above its co-engaging projection 20, the armature 11 of the box having its lever 59 in such elevated position will retract upon the withdrawal of the restraint of the determining lever 16 therefrom, and permit its latch arm 83 to move to its lower position, after which the operation of such box will be the same as that described in the case of a box pulled while another box was transmitting its signal.

The operation of this box if pulled when the strength of the line current is abnormally low is as follows: It has already been pointed out that, when this box is pulled, the hook 84 lies in the path of the projection 19 so that it will not permit the determining lever 16 to move with the armature 11, and therefore the movement of the armature to its attracted position is resisted by the force of the spring 18 in addition to the force of the spring 15. Hence the armature 11 will remain in retracted position unless the line current is strong enough to so energize the magnet 12 as to overcome both of these springs and thus withdraw the detent 91 from the path of the fan 29. When the magnet is so energized, the train will commence running and thereupon the tongue 87 will raise the arm 83 somewhat higher, thus first imparting an additional retractile force to the armature 11 through the additional stretching of the spring 15. If the train is not stopped on account of such additional retractile force, the hook 84 will be raised above the level of the projection 19, and the end 17 of the determining lever 16 will move against the armature 11 thereby relieving said armature from the retractile force of the spring 18 and leaving it subject only to the retractile force of the spring 15.

From the foregoing it is apparent that any line current strength which is sufficient to cause the armature 11 to move to release the train from the detent 91 against the retractile force of the spring 18 while the hook 84 is in the path of the projection 19, will be sufficient to retain the armature 11 in its attracted position during the closed

circuit periods incident to the transmission of the signal of this box, and it will thus be seen that any current strength which will permit a signal to be initiated will retain the armature in attracted position throughout the transmission of such signal.

After this box has been interfered with, and has come to rest due to a circuit interruption incident to the transmission of the signal of some other box, the current strength may thereafter be so substantially decreased (as from the serial inclusion in its circuit of the magnets of a plurality of other boxes which may be pulled at or about the same time) that, with the normal tension of the spring 15, the added air gap between the armature and magnet, and the friction incident to withdrawing the detent 91 from engagement with the fan 29, the armature would not be moved to attracted position even though the line current was still strong enough to assure the transmission of a signal if the train was once started, but, owing to the peculiar construction of this box, the tension of the retractile spring 15 is substantially decreased whenever the latch arm 83 swings to its lower position, so that the armature 11 will be permitted to move to attracted position upon a comparatively slight energization of the magnet 12. However, even under these circumstances the transmission of a signal will not be initiated unless the line current strength is sufficient to insure the completion of such signal, for the reason that the latch arm 83 must be raised by the tongue 87 before a signal can be initiated when the box has once been interfered with, and when so raised the spring 15 will be restored to substantially normal tension and the face 85 of the hook 84 carried by said latch arm will act against the projection 19 to stretch the spring 18 so as to tend to move the armature 11 to retracted position, and the strength of said springs 15 and 18 is so proportioned to the power and permeability of the magnet 12 and armature 11 that unless the current through magnet 12 is sufficient to so energize said magnet as to prevent retraction of the armature 11 under the tension of the retractile spring 15 within the time which elapses during each closure of the signaling contacts while the free end of the signaling lever 59 is out of the path of the projection 20, said spring 15 will cause the retraction of said armature and prevent the initiation of the signal.

Having now fully described our invention, what we claim and desire to secure by Letters Patent of the United States is:

1. A signaling train, signaling contacts operable thereby, a noninterference magnet, an armature therefor, disabling means controlled by said armature constantly tending to act to render said contacts unrespon-

sive to the running of the train, an actuating spring, one end of which is connected to said means, and the other end to the armature so that when the signaling contacts are disabled by said means the force applied to said armature by said spring will be substantially less than when said signaling contacts are free to act.

2. A signaling train; signaling contacts operable thereby; a noninterference magnet; an armature therefor; disabling means controlled by said armature adapted to render said contacts unresponsive to the running of the train; an actuating spring, one end of which is connected to said means, and the other end to the armature; and means operated by the train in running for moving the disabling means to adjust said spring to a maximum tension at predetermined intervals during the running of the train.

3. A signaling train; signaling contacts operable thereby; a noninterference magnet; an armature therefor; disabling means controlled by said armature adapted to render said contacts unresponsive to the running of the train; an actuating spring, one end of which is connected to said means, and the other end to the armature; means operated by the train in running for moving said disabling means to adjust said spring to a maximum tension at predetermined intervals during the running of the train; and means governed by the position of the armature for retaining said maximum tension while the armature remains in attracted position.

4. A signaling train; signaling contacts operable thereby; a noninterference magnet; an armature therefor; disabling means controlled by said armature adapted to render said contacts unresponsive to the running of the train; an actuating spring, one end of which is connected to said means, and the other end to the armature; means operated by the train in running for moving the disabling means to adjust said spring to a maximum tension at predetermined intervals during the running of the train; and means governed by the position of the armature for retaining said maximum tension while the armature remains in attracted position, and for decreasing said tension upon retraction of the armature.

5. A signaling train; signaling contacts operable thereby; a noninterference magnet; an armature therefor; disabling means controlled by said armature adapted to render said contacts unresponsive to the running of the train when in one position, and adapted to assume a second position rendering said contacts responsive to the running of the train; an actuating spring, one end of which is connected to said means, and the other end to the armature, and means

governed by the position of the disabling means for suitably varying the tension of said spring.

6. A signaling train; signaling contacts operable thereby; a noninterference magnet; an armature therefor; disabling means controlled by said armature adapted to render said contacts unresponsive to the running of the train when in one position, and adapted to assume a second position rendering said contacts responsive to the running of the train; an actuating spring, one end of which is connected to said means, and the other end to the armature, and means governed by the position of the disabling means for decreasing the tension of said retractile spring whenever said disabling means has acted in response to the retraction of said armature.
- 20 7. A signaling train; signaling contacts operable thereby; a noninterference magnet; an armature therefor; spring actuated disabling means constantly tending to act to render said contacts unresponsive to the running of the train; and a determining lever for said disabling means so connected with said armature that it may be positively moved in one direction by the retractive movement of said armature to disengage the disabling means permitting it to operate, and that it may be yieldingly moved in the opposite direction by the attractive movement of said armature to admit of the engagement of the disabling means there-
- 25 with.

8. A signaling train; signaling contacts operable thereby; a noninterference magnet; an armature therefor; disabling means constantly tending to act to render said contacts unresponsive to the running of the train when in one position, and adapted to be moved by the train to a second position rendering said contacts responsive to the running of the train; and a determining lever so connected with said armature that it may be positively moved in one direction upon the retractive movement of said armature, and that it may be yieldingly moved in the opposite direction upon the attractive movement of said armature; said determining lever being adapted to hold said disabling means in the position to which it may be moved by the train, and so arranged that upon movement of said armature to retracted position, said disabling means will not be so held.

9. A signaling train; signaling contacts operable thereby; a noninterference magnet; an armature therefor; disabling means constantly tending to act to render said contacts unresponsive to the running of the train; and a determining lever operated by the retraction of the armature adapted to hold said disabling means ineffective and adapted to be engaged by a part moving

with said signaling contacts to hold said armature in attracted position whenever the signaling contacts are in a predetermined position.

10. A signaling train; signaling contacts operable thereby; a noninterference magnet; an armature therefor; spring actuated disabling means constantly tending to act to render said contacts unresponsive to the running of the train; and a determining lever for said disabling means associated with said armature and adapted to move independently thereof, a portion of said lever being disposed in the path of said armature to be positively moved by said armature upon retraction thereof and means controlled by the train in running to place the disabling means under the control of the determining lever, and also to restore it from disabling position.

20 11. A signaling train; signaling contacts operable thereby; a noninterference magnet; an armature therefor; spring actuated disabling means constantly tending to act to render said contacts unresponsive to the running of the train; and a determining lever for said disabling means associated with said armature and adapted to move independently thereof, a portion of said lever being disposed in the path of said armature to be positively moved by said armature upon retraction thereof; said determining lever being adapted to hold said disabling means ineffective and means controlled by the train in running to place the disabling means under the control of the determining lever, and also to restore it from disabling position.

25 12. A signaling train; signaling contacts operable thereby; a noninterference magnet; an armature therefor; disabling means constantly tending to act to render said contacts unresponsive to the running of the train; and a determining lever adapted to hold said disabling means ineffective, said determining lever being adapted to be moved out of the path of the coengaging part of said disabling means upon a comparatively slight retractive movement of said armature, and to be moved by the disabling means out of the path thereof while the armature is in attracted position.

30 13. A signaling train; signaling contacts operable thereby; a noninterference magnet; an armature therefor; disabling means constantly tending to act to render said contacts unresponsive to the running of the train; and a determining lever adapted to hold said disabling means ineffective, and so governed by the armature that upon movement of said armature to retracted position the disabling means will not be so held; the train operating to move the signaling contacts into position to be engaged by the disabling means, to be thereby prevented from

120
125
130

controlling the circuit, a releasing means for the train adapted for operation upon a very slight movement of the armature, and the frictional engagement of said releasing means with the train being comparatively slight.

14. A signaling train; signaling contacts operable thereby; a noninterference magnet; an armature therefor; disabling mechanism adapted to render said contacts unresponsive to the running of the train when in one position, and adapted to assume a second position rendering said contacts responsive to the running of the train; operating means constantly tending to act to move said disabling mechanism to its said first named position; a connection with the train to move said operating means to a position where it will permit said disabling mechanism to move to its said second named position; and a determining lever adapted to hold said operating means in the position to which it may be moved by the train, and so governed by the armature that upon movement of said armature to retracted position the operating means will not be so held; the train operating to move the signaling contacts into position to be engaged by the disabling means, to be thereby prevented from controlling the circuit, a releasing means for the train adapted for operation upon a very slight movement of the armature, and the frictional engagement of said releasing means with the train being comparatively slight.

15. A signaling train; signaling contacts operable thereby; a noninterference magnet; an armature therefor; disabling mechanism adapted to render said contacts unresponsive to the running of the train when in one position, and adapted to assume a second position rendering said contacts responsive to the running of the train; operating means constantly tending to act to move said disabling mechanism to its said first named position; a connection with the train to move said operating means to a position where it will permit said disabling mechanism to move to its said second named position; and a determining lever adapted to hold said operating means in the position to which it may be moved by the train, and so governed by the armature that upon movement of said armature to retracted position the operating means will not be so held.

16. A signaling train; signaling contacts operable thereby; a noninterference magnet; an armature therefor; disabling mechanism adapted to render said contacts unresponsive to the running of the train when in one position, and adapted to assume a second position rendering said contacts responsive to the running of the train; operating means constantly tending to act to

move said disabling mechanism to its said first named position, and so applied thereto as to act at substantially greater advantage when said disabling mechanism is in its said second named position than when said disabling mechanism is in its said first named position; and a determining lever adapted to hold said operating means in the position where it is acting at greatest advantage, said determining lever being adapted to be moved out of the path of the coengaging part of said operating means upon a comparatively slight retractive movement of said armature.

17. A signaling train; signaling contacts operable thereby; a noninterference magnet; an armature therefor; disabling mechanism adapted to render said contacts unresponsive to the running of the train when in one position, and adapted to assume a second position rendering said contacts responsive to the running of the train; operating means constantly tending to act to move said disabling mechanism to its said first named position, and so applied thereto as to act at substantially greater advantage when said disabling mechanism is in its said second named position than when said disabling mechanism is in its said first named position; and a determining lever adapted to hold said operating means in the position where it is acting at greatest advantage, said determining lever being adapted to be moved out of the path of the coengaging part of said operating means upon a comparatively slight retractive movement of said armature, and to be moved by the operating means out of the path thereof while the armature is in attracted position.

18. A signaling train; a signal wheel therefor; a circuit controlling contact arranged to be raised by the signal wheel when the circuit is to be closed, and to be allowed to fall to open the circuit; a noninterference magnet; an armature therefor; and disabling means controlled by said armature for moving said circuit controlling contact to a position above that to which it may be moved by said signal wheel.

19. A signaling train; a signal wheel therefor; a circuit opening contact arranged to be raised by the signal wheel when the circuit is to be closed, and to be allowed to fall to open the circuit; a circuit closing contact arranged to be raised by the signal wheel when the circuit has been opened, and to be allowed to fall to close the circuit; a noninterference magnet; an armature therefor; and disabling means controlled by said armature for holding said circuit opening contact in engagement with said circuit closing contact in spite of the action of the signal wheel upon said circuit closing contact.

20. A signaling train; signaling contacts

operable thereby; a noninterference magnet; an armature therefor; disabling mechanism adapted to render said contacts unresponsive to the running of the train; a latch arm adapted to be controlled by said armature, and adapted to move said disabling mechanism to disabling position; and an operating spring for said latch arm so applied thereto that when said latch arm is in control 10 of said armature the operative effect of said spring upon said latch arm will be applied thereto at only such advantage as to be capable of safely moving said latch arm against the friction of its pivot, and so that 15 the operative effect of said spring will be applied to said latch arm when said latch arm has moved out of control of said armature at such advantage as to be capable of safely moving said latch arm to operate the disabling mechanism.

21. A signaling train; signaling contacts operable thereby; a noninterference magnet; an armature therefor; disabling mechanism adapted to render said contacts unresponsive to the running of the train; a determining lever connected with said armature; a latch arm adapted to be latched by said determining lever, and adapted to move said disabling mechanism to disabling position; 25 and an operating spring for said latch arm so applied thereto that when said latch arm is in engagement with said determining lever the operative effect of said spring upon said latch arm will be applied thereto at only such advantage as to be capable of safely moving said latch arm against the friction of its pivot, and so that the operative effect of said spring will be applied to said latch arm when said latch arm has moved out of 30 engagement with said determining lever at such advantage as to be capable of safely moving said latch arm to operate the disabling mechanism.

22. A signaling train; signaling contacts operable thereby; a noninterference magnet; an armature therefor; disabling mechanism adapted to render said contacts unresponsive to the running of the train; a determining lever connected with said armature; a latch arm adapted to be latched by said determining lever, and adapted to move said disabling mechanism to disabling position; a connection with the train to move said latch arm to latching position; 50 and an operating spring for said latch arm so applied thereto that when said latch arm is in engagement with said determining lever the operative effect of said spring upon said latch arm will be applied thereto at only such advantage as to be capable of safely moving said latch arm against the friction of its pivot, and so that the operative effect of said spring will be applied to said latch arm when said latch arm has

moved out of engagement with said determining lever at such advantage as to be capable of safely moving said latch arm to operate the disabling mechanism. 65

23. A signaling train; signaling contacts operable thereby; a noninterference magnet; an armature therefor; a determining lever connected with said armature; disabling means adapted to render said contacts unresponsive to the running of the train when in one position, and adapted to assume a second position rendering said contacts responsive to the running of the train; said disabling means comprising a latch arm and an actuating spring constantly tending to move said arm in one direction, said latch 70 arm being adapted to such coengagement with the determining lever that said arm may be caught and held when it has moved to the limit of its travel in opposition to such tendency when the determining lever is 75 in a certain position, and whereby said coengagement will not occur at any other time, manual starting means for the train adapted to move said latch arm into position to hold the determining lever, and further movable by the train to a position for locking 80 engagement with said lever.

24. A signaling train; signaling contacts operable thereby; a noninterference magnet; an armature therefor; a determining lever connected with said armature; disabling means constantly tending to act to render said contacts unresponsive to the running of the train when in one position, and adapted to assume a second position 95 rendering said contacts responsive to the running of the train; said disabling means comprising a spring-actuated latch arm having a hook so positioned with relation to the determining lever that a projection from 100 said determining lever will lie in the path of said hook when said lever is in one position and will be withdrawn from the path of said hook when said lever is in another position, manual starting means for the train 105 for moving the latch arm into position to prevent movement of the determining lever, and further movable by the train to move it into position for locking engagement with said lever. 110

25. A signaling train; signaling contacts operable thereby; a noninterference magnet; an armature therefor; a determining lever yieldingly connected with said armature; disabling means constantly tending to act 115 to render said contacts unresponsive to the running of the train when in one position, and adapted to assume a second position rendering said contacts responsive to the running of the train; said disabling means comprising a latch arm having a hook so positioned with relation to the determining lever that a projection from 120 said determining lever will lie in the path of said hook when said lever is in one position and will be withdrawn from the path of said hook when said lever is in another position, manual starting means for the train 125 for moving the latch arm into position to prevent movement of the determining lever, and further movable by the train to move it into position for locking engagement with said lever.

- ing lever will lie in the path of said hook when said lever is in one position, and will be withdrawn from the path of said hook when said lever is in another position; said hook being so formed that when the determining lever is in position to be engaged by said hook and the latch arm is moved to carry said hook past the coengaging portion of the determining lever in one direction
- 10 the engagement between said hook and the determining lever will cause the coengaging portion of said lever to be moved out of the path of said hook and movement of the latch arm to carry said hook past the coengaging portion of the determining lever in the other direction will be prevented.
26. A signaling train, signaling-contacts operable thereby, a non-interference magnet, an armature therefor, a determining-lever connected with said armature, a holder adapted to render said contacts unresponsive to the running of the train, a latch arm adapted to be controlled by said determining-lever and to be operated by the train, a cam operated by said latch arm and adapted to engage the holder whereby the movement of the latch arm in one direction may move the holder to disable the signaling-contacts, permitting said holder to be retained in disabling position without thereby disturbing the movement of the latch arm.
27. A signaling train, signaling-contacts operable thereby, a non-interference magnet, an armature therefor, a determining-lever connected with said armature, a holder adapted to render said contacts unresponsive to the running of the train, a latch arm adapted to be controlled by said determining-lever to be operated by the train, a cam operated by the latch arm and adapted to engage the holder whereby the latch arm will not act to cause movement of the holder when moved from the position where it may be engaged by the determining-lever until it is moved a predetermined distance from said engaging position.
28. A signaling train, signaling contacts operable thereby, a noninterference magnet, an armature therefor, a holder adapted to render said contacts unresponsive to the running of the train, a latch arm adapted to be controlled by said armature, and a cam face moving with the latch arm for imparting movement to said holder in one direction when the latch arm is moving away from the position where it may be controlled by said armature, thereby to hold the signaling contacts out of the control of the signal wheel.
- 60 29. A signaling train; a signal wheel therefor; a signaling lever operable by said signal wheel; a noninterference magnet; an armature therefor; a holder controlled by said armature adapted to render said sig-
- naling lever unresponsive to said signal wheel; said holder having a shoulder, and a catch arm pivoted on the signaling lever, the free end of which is adapted to engage with the signal wheel and the catch of which is adapted to engage the shoulder on the holder when said holder is in disabling position, thereby to hold the signaling contacts in unresponsive position.
30. A signaling train; a signal wheel therefor; a signaling lever operable by said signal wheel; a noninterference magnet; an armature therefor; a holder controlled by said armature adapted to render said signaling lever unresponsive to said signal wheel; a catch arm pivoted on the signaling lever, the free end of which is adapted to engage with the signal wheel and the catch of which is adapted to engage the holder when said holder is in disabling position; thereby to hold the signaling contacts in unresponsive position and an operating spring so applied to said catch arm as to tend to maintain the signaling lever and the free end of the catch arm in engagement with the signal wheel.
31. A signaling train; a signal wheel therefor; a signaling lever operable by said signal wheel; a noninterference magnet; an armature therefor; a holder controlled by said armature adapted to render said signaling lever unresponsive to said signal wheel; a catch arm pivoted on the signaling lever, the free end of which is adapted to engage with the signal wheel and the catch of which is adapted to engage the edge of the holder when said holder is in disabling position; thereby to hold the signaling contacts in unresponsive position, and an operating spring connected to the catch arm at such point that the pivot of said arm is at one side thereof and the catch and the end for engaging the signal wheel are at the other side thereof.
32. A signaling train; a signal wheel therefor; a signaling lever operable by said signal wheel; a noninterference magnet; an armature therefor; a holder controlled by said armature adapted to render said signaling lever unresponsive to said signal wheel; a catch arm pivoted on the signaling lever, the free end of which is adapted to engage with the signal wheel, and the catch of which is adapted to engage the edge of the holder when said holder is in disabling position; thereby to hold the signaling contacts in unresponsive position and an operating spring so applied to said catch arm that either the end of said arm resting upon said signal wheel or the catch may act as a fulcrum around which said arm may be rocked by said spring to hold the signaling lever in engagement with the signal wheel.
33. A signaling train; a signal wheel therefor; a circuit controlling contact ar-

ranged to be raised by the signal wheel when the circuit is to be closed, and to be allowed to fall to open the circuit; a noninterference magnet; an armature therefor; disabling means controlled by said armature for raising said circuit controlling contact to a position above that to which it may be raised by said signal wheel and adapted to assume a second position where it will release said circuit controlling contact; and means operable by the train whereby the movement of the disabling means from its said first named position to its said second named position will be permitted only when the signal wheel is in position to support the circuit controlling contact in elevated position.

34. A signaling train; a signal wheel therefor; a circuit opening contact arranged to be raised by the signal wheel when the circuit is to be closed, and to be allowed to fall to open the circuit; a circuit closing contact arranged to be raised by the signal wheel when the circuit has been opened, and to be allowed to fall to close the circuit; said contacts being so arranged that the circuit opening contact will not be sufficiently raised by the signal wheel to establish a connection with the circuit closing contact when said circuit closing contact has been raised to the limit of the travel which may be imparted thereto by said signal wheel; a noninterference magnet; an armature therefor; disabling means controlled by said armature for raising said circuit opening contact to a position above that to which it may be raised by said signal wheel and adapted to assume a second position where it will release said circuit opening contact; and means operable by the train whereby the movement of the disabling means from its said first named position to its said second named position will be permitted only when the signal wheel is in position to support the circuit opening contact and permits the circuit closing contact to connect with said circuit opening contact.

35. A signaling train; a signal wheel therefor; a circuit opening contact arranged to be raised by the signal wheel when the circuit is to be closed, and to be allowed to fall to open the circuit; a circuit closing contact arranged to be raised by the signal wheel when the circuit has been opened, and to be allowed to fall to close the circuit; said contacts being so arranged that the circuit opening contact will not be sufficiently raised by the signal wheel to establish a connection with the circuit closing contact when said circuit closing contact has been raised to the limit of the travel which may be imparted thereto by said signal wheel; a noninterference magnet; an armature therefor; disabling means controlled by said armature for raising said circuit opening

contact to a position where it will hold said circuit closing contact above the position to which it may be raised by said signal wheel while said disabling means is in one position, and adapted to assume a second position where it will release said circuit closing contact; and means operable by the train whereby the movement of the disabling means from its said first named position to its said second named position will be permitted only when the signal wheel is in position to support the circuit opening contact and permits the circuit closing contact to connect with said circuit opening contact.

36. A signaling train; a signal wheel therefor; a circuit opening contact arranged to be raised by the signal wheel when the circuit is to be closed, and to be allowed to fall to open the circuit; a circuit closing contact arranged to be raised by the signal wheel when the circuit has been opened, and to be allowed to fall to close the circuit; said contacts being so arranged that the circuit opening contact will not be sufficiently raised by the signal wheel to establish a connection with the circuit closing contact when said circuit closing contact has been raised to the limit of the travel which may be imparted thereto by said signal wheel; a noninterference magnet; an armature therefor; and disabling means controlled by said armature for raising said circuit opening contact to a position where it will hold said circuit closing contact above the position to which it may be raised by said signal wheel while said disabling means is in one position, and for holding said circuit opening contact against such movement as will enable it to retain connection with the circuit closing contact when said circuit closing contact has been raised to the limit of the travel which may be imparted thereto by said signal wheel while said disabling means is in another position.

37. A signaling train; a signal wheel therefor; a circuit opening contact arranged to be raised by the signal wheel when the circuit is to be closed, and to be allowed to fall to open the circuit; a circuit closing contact arranged to be raised by the signal wheel when the circuit has been opened, and to be allowed to fall to close the circuit; said contacts being so arranged that the circuit opening contact will not be sufficiently raised by the signal wheel to establish a connection with the circuit closing contact when said circuit closing contact has been raised to the limit of the travel which may be imparted thereto by said signal wheel; a noninterference magnet; an armature therefor; disabling means controlled by said armature for raising said circuit opening contact to a position where it will hold said circuit closing contact above the position to which it

may be raised by said signal wheel while said disabling means is in one position, and for holding said circuit opening contact against such movement as will enable it to 5 retain connection with the circuit closing contact when said circuit closing contact has been raised to the limit of the travel which may be imparted thereto by said signal wheel while said disabling means is in another 10 position; and means operable by the train whereby the movement of the disabling means from its said first named position to its said second named position will be permitted only when the signal wheel is 15 in position to support the circuit opening contact and permits the circuit closing contact to connect with said circuit opening contact.

38. A signaling train, a noninterference 20 magnet, an armature therefor, manually disengageable stopping mechanism for the train, a restoring lever controlled by the stopping mechanism, and a detent for the train connected to the armature and so pivoted to said 25 restoring lever, that when the stopping mechanism is in one position said detent will act upon each retraction of the armature to suspend the running of the train and when the stopping mechanism is in another position 30 said detent will be rendered ineffective.

39. A signaling train, signaling contacts 35 operable thereby, a noninterference magnet, an armature therefor, disabling mechanism adapted to render said contacts unresponsive to the running of the train, a latch arm controlled by said armature and adapted to move said disabling mechanism to disabling 40 position, manually disengageable stopping mechanism for the train, a restoring lever controlled by the stopping mechanism, and a pivot for the latch arm mounted upon said 45 restoring lever in such position that when the stopping mechanism is in position to stop the train the disabling mechanism will be moved to disabling position regardless of the position of the latch arm.

40. A signaling train; signaling contacts 50 operable thereby; a noninterference magnet; an armature therefor; disabling mechanism adapted to render said contacts unresponsive to the running of the train when in one position, and adapted to assume a second position rendering said contacts responsive to the running of the train; operating means 55 controlled by said armature constantly tending to act to move said disabling mechanism to its said first named position; manually disengageable stopping mechanism for the train; a restoring lever controlled by the 60 stopping mechanism; a connection operated thereby for moving the disabling mechanism to its said first named position independent of the release of said operating means; and an arm moving with the stopping mecha-

nism for moving said restoring lever to one 65 position when the stopping mechanism has been manually moved to disengaged position and for moving said restoring lever to another position when the stopping mechanism is in position to stop the train.

41. A signaling train; signaling contacts 70 operable thereby; a noninterference magnet; an armature therefor; spring actuated disabling means constantly tending to act to render said contacts unresponsive to the running 75 of the train; the actuating spring for said means being connected at one end with said means, and at the other end with the armature to serve as a retractile means therefor, and being arranged to be applied 80 thereto with varying force so as to apply a substantially greater retractile force to said armature just prior to the initiation of a signal than the retractile force applied to said armature 85 during the transmission of any signal.

42. A signaling train; signaling contacts 90 operable thereby; a noninterference magnet; an armature therefor; spring actuated disabling means constantly tending to act to render said contacts unresponsive to the running 95 of the train; the actuating spring of said means being connected at one end with said means, and at the other end with the armature to also serve as retractile means therefor, and being so controlled by the disabling means as to apply a substantially greater retractile force to said armature just prior to the initiation of a signal than the retractile force applied to said armature 100 during the transmission of any signal.

43. A signaling train; signaling contacts 105 operable thereby; a noninterference magnet; an armature therefor; disabling means adapted to render said contacts unresponsive to the running of the train when in one position, and adapted to assume a second position rendering said contacts responsive to the running of the train; a connection with the train to move said disabling means to 110 its said second named position; a determining lever adapted to hold said disabling means in the position to which it may be moved by the train, and so governed by the armature that upon movement of said 115 armature to retracted position the disabling means will not be so held; and means tending to keep said determining lever in the path of the part of the disabling means adapted to engage therewith while the armature is in attracted position, whereby the 120 retractile force applied to said armature will be materially increased when the disabling means is being so moved by the train.

44. A signaling train; signaling contacts 125 operable thereby; a noninterference magnet; an armature therefor; disabling mechanism adapted to render said contacts unresponsive

to the running of the train when in one position, and adapted to assume a second position rendering said contacts responsive to the running of the train; operating means 5 constantly tending to move said disabling mechanism to its said first named position; a connection with the train to move said operating means to a position where it will permit said disabling mechanism to move, 10 to its said second named position; a determining lever adapted to hold said operating means in the position to which it may be moved by the train, and so governed by the armature that upon movement of said armature to retracted position the operating means will not be so held; and means tending to keep said determining lever in the path of the part of the operating means adapted to engage therewith while the armature 15 is in attracted position, whereby the retractile force applied to said armature will be materially increased when the operating means is being so moved by the train.

45. A signaling train; signaling contacts operable thereby; a noninterference magnet; 20 an armature therefor; disabling mechanism

adapted to render said contacts unresponsive to the running of the train when in one position, and adapted to assume a second position rendering said contacts responsive to 30 the running of the train; operating means governed by said armature and constantly tending to move said disabling mechanism to its said first named position; a connection with the train to move said operating means 35 to a position where it will permit said disabling mechanism to move to its said second named position; and a retractile spring for said armature adapted to be so influenced by said operating means that the retractile force 40 applied to said armature will be materially decreased when the operating means has been so moved by the train.

In witness whereof, we have hereunto subscribed our names this 18th day of February, 45 A. D., 1915.

C. E. BEACH.
